UNITED STATES PATENT OFFICE

ARCHIBALD D. EVANS AND JAMES K. LAMOREE, OF NEW CASTLE, PENNSYLVANIA,
ASSIGNORS TO AMERICAN SHEET AND TIN PLATE COMPANY, OF PITTSBURGH,
PENNSYLVANIA, A CORPORATION OF NEW JERSEY

PILE AND PACKING APPARATUS

Application filed September 28, 1927. Serial No. 222,680.

This invention relates to packing and piling apparatus for packing and piling sheets and plates in connection with tin mill apparatus and, while not limited thereto, relates more particularly to an automatic sheet and plate packer and piler for use in connection with cold mills and similar apparatus.

Heretofore sheets and plates passing from the cold mill have generally been packed or piled by hand on an annealing stand or other support in readiness for the next operation which generally is an annealing operation.

The present invention provides an automatic packer and piler which entirely dispenses with the manual labor heretofore used to pack and pile the sheets and plates.

In the drawings—

Figure 1 is a plan view of a packer and piler constructed in accordance with this invention.

Figure 2 is a side elevation thereof.

Figure 3 is a perspective elevation of a modified form of stop and guide member.

Referring more particularly to the drawings, the numeral 2 designates a conveyer for delivering the sheets and plates to be packed and piled.

The packer and piler comprises a frame 3 in which is journaled a concave feed roller 4. A convex feed roller 5 is journaled in a pair of arms 5^a pivotally secured to the frame 3. A screw shaft 6 is journaled in the frame 3 and is provided with a crank handle 7 by which it may be rotated. A pair of right and left-hand threaded nuts 8 and 9, respectively, are threaded on the shaft 6 and are supported by a rest bar or rail 10.

A pair of side bars 12 and 13 are secured to the nuts 8 and 9, respectively. Each of the bars 12 and 13 is provided with a side guide-plate 15 which is flared outwardly at its upper edge, as at 16.

A mounting disk 17 is provided with diametrically opposite screw threaded arms 18, which arms project through apertures adjacent the rear ends of the side bars 12 and 13, and are held in place by jam-nuts 19.

The disk 17 is provided with a centrally disposed aperture in which a threaded bar 20 is slidably mounted. A pair of jam-nuts 21

are provided on the bar 20 for locking said bar in position in said disk.

A combined stop and guide-plate 22 is secured to the inner end of the bar 20 and comprises a vertical pile forming portion *a*, and a curved guide portion *b*. The curved guide portion *b* of the plate 22 is bent forwardly in the direction of travel of the sheets and plates, from the upper end of the vertical pile forming portion *a*, and then curved rearwardly and upwardly so as to extend materially rearward of the vertical plane of the vertical portion *a*.

A rear pile guide 24 is secured to the frame 3 to guide the rear end of the sheets and plates.

An annealing box base 25 or other support is adapted to be located below the packing and piling mechanism to receive the pile of sheets or plates.

In operation the sheets or plates, designated by the letter Y, are fed into the bite of the feed rollers 4 and 5 of the packer and piler. The rollers 4 and 5, due to their respective concave and convex shape, will bend the sheets or plates transversely as they pass between the rollers, thereby stiffening the sheets and plates so as to prevent them dipping or sagging. The rollers 4 and 5 will project the sheets or plates forwardly against the stop-plate 22 at a point adjacent its upper end and due to the novel curved shape of the stop-plate 22, the forward end of the sheet or plate will be guided downwardly while it is still being projected forward. The curve of the stop-plate 22 is sufficient to permit the sheets or plates being piled to pass from between the rollers 4 and 5, and after the sheet or plate leaves the rollers 4 and 5 it will then fall between the side guide-plates 15 and at the same time, the forward end of the sheet or plate will engage the lower part of the curved portion *b* of the stop-plate 22 and be forced rearwardly so as to fall between the portion *a* of the stop-plate 22 and the rear guide 24 and form a neat even pile on the support 25.

In order to adjust this apparatus for different sized sheets or plates, the jam-nuts 19 and 21 are loosened, and the shaft 6 is ro-

100

tated by means of the handle 7 so as to cause the nuts 8 and 9, to travel along the shaft 6, either toward or away from each other, as desired.

Since the side bars 12 are secured to the nuts 8 and 9, the bars 12 and side-guides 15 will be moved with the nuts 8 and 9. After the side-guides 15 are correctly positioned the jam-nuts 19 will be tightened so as to center the shaft or bar 20 carrying the stop and guide-plate 22. The bar or shaft 20 will then be moved forward or rearward, as desired, to correct position and the jam-nuts 21 tightened to lock the plate 22 in position.

In Figure 3 we have shown a slightly modified form of stop and guide-member 22^a, composed of a plurality of bars or fingers 30 mounted in a base 31 and having the guide-portion *b* and pile forming portion *a*.

While we have shown and described one embodiment of our invention it will be understood that we do not wish to be limited thereto since various modifications may be made without departing from the scope of our invention as defined in the appended claims.

We claim—

1. In a sheet mill apparatus, means for feeding sheets and plates out over a support, and a stop for limiting the movement of said sheets and plates and for causing said sheets and plates to descend by gravity in an orderly manner forming a pile, said stop comprising a wall member having a straight vertical pile forming portion and a curved guide portion, said curved guide portion being bent forwardly from the upper end of said vertical portion in the direction of travel of said sheets and plates and then rearwardly and upwardly, said curved guide portion being adapted to engage the forward ends of the plates and sheets and direct said sheets and plates downwardly toward said support.

2. In a sheet mill apparatus, a pair of feed rollers adapted to project sheets and plates to be piled out over a support and a stop for limiting the movement of said sheets and plates and for causing said sheets and plates to descend by gravity in an orderly manner forming a pile on said support, said stop being adjustable toward and away from said rolls, said stop comprising a wall member having a straight vertical pile forming portion and a curved guide portion, said curved guide portion being bent forwardly from the upper end of said vertical portion in the direction of travel of said sheets and plates and then rearwardly and upwardly, said curved guide portion being adapted to engage the forward ends of the sheets and plates and direct said sheets and plates downwardly toward said support.

3. In a sheet mill apparatus, a pair of feed rollers adapted to project sheets and plates to be piled out over a support, one of said

rollers being convex and the other of said rollers being concave whereby said sheets and plates are curved transversely so as to stiffen them and cause them to be projected over said support without dipping or bending, and a stop for limiting the movement of said sheets and plates and for causing said sheets and plates to descend by gravity in an orderly manner forming a pile on said support, said stop being adjustable toward and away from said rolls, said stop comprising a wall member having a straight vertical pile forming portion and a curved guide portion, said curved guide portion being bent forwardly from the upper end of said vertical portion in the direction of travel of said sheets and plates and then rearwardly and upwardly, said curved guide portion being adapted to engage the forward ends of the plates and sheets and direct said sheets and plates downwardly toward said support.

4. An automatic packer and piler for sheets and plates, comprising a pair of feed rollers adapted to project the sheets and plates out over and above a support, one of said rollers being concave and the other of said rollers being convex whereby said sheets and plates are curved transversely so as to stiffen them and cause them to project over said support without dipping or bending, a pair of adjustable side-guides, and a stop for limiting the forward movement of said sheets and plates and for causing said sheets and plates to descend by gravity in an orderly manner between said side-guides and onto said support forming a pile, said stop being adjustable toward and away from said rollers, said stop comprising a wall member having a straight vertical pile forming portion and a curved guide portion, said curved guide portion being bent forwardly from the upper end of said vertical portion in the direction of travel of said sheets and plates and then rearwardly and upwardly, said curved guide portion being adapted to engage the forward ends of the plates and sheets and direct said sheets and plates downwardly toward said support.

5. An automatic packer and piler for sheets and plates, comprising a pair of feed rollers adapted to project the sheets and plates out over and above a support, one of said rollers being concave and the other of said rollers being convex whereby said sheets and plates are curved transversely so as to stiffen them and cause them to be projected over said support without dipping or bending, a pair of adjustable side-guides and a stop for limiting the forward movement of said sheets and plates and for causing said sheets and plates to descend by gravity in an orderly manner between said side-guides and onto said support forming a pile, said stop comprising a plate having a straight vertical pile forming portion and a curved

guide portion, said curved guide portion being bent forwardly from the upper end of said vertical portion in the direction of travel of said sheets and plates, and then rearwardly and upwardly, said curved guide portion being adapted to engage the forward ends of the sheets and plates and direct said sheets and plates downwardly toward said support, and screw means for adjusting said stop toward and away from said rollers.

5 In testimony whereof, we have hereunto signed our names.

10 ARCHIBALD D. EVANS.
JAMES K. LAMOREE.
